TOWEL HOLDER

Vincent Panettiere, Brooklyn, N. Y.

Application May 19, 1933, Serial No. 671,780

3 Claims. (Cl. 211—16)

This invention relates in general to fastening devices and is more particularly concerned with means for holding towels and the like.

It is an object of the present invention to provide a fastening device of the character described, which is especially adapted to support towels and the like and is so designed and constructed as to clampingly engage the towel in such a manner as to obviate the possibility of its becoming torn while being used.

It is a further object to provide a holder having means to clampingly engage the towel in such a manner that the towel will be more firmly gripped as the pull on the towel is increased.

It is also an object to provide a device of this character which is constructed in such a way that a towel or similar article may be easily engaged and released, and when engaged will be firmly gripped and held against removal.

Still another object is to provide such a device wherein the article secured is firmly held against removal without having to utilize teeth or other piercing elements which would have a tendency to tear or otherwise damage the article.

In accordance with the general features of the invention, I provide a frame including a round transverse bar which is rigidly secured thereto. Slidably mounted on the frame is a curved plate which may be moved into and away from the fixed bar. The curved plate projects a greater amount on one side past the plane of the frame than it does on the other. This plate has an inner surface conforming to that of the fixed bar so that, when the plate is moved into clamping position with the fixed bar, a large clamping surface is operative to hold the towel or other article against slipping. Moreover, by passing the towel end over the sliding plate and then back between the plate and bar, after which the plate is pushed into clamping engagement with the bar, the towel will be firmly held against slipping and there are no penetrating elements to tear or otherwise damage the towel.

The curved plate is secured to the frame in such a manner that it may be slightly tilted relative to the frame. It will be observed that as the pull is increased on the body of the towel or other article, the forces are such as to tend to tilt the plate relative to the frame, this action causing the plate to be more strongly forced against the fixed bar, the clamping forces thereby being increased.

While the invention has been illustrated and will be described in connection with a towel, it will be apparent to one skilled in the art, that

the invention is susceptible of many other uses as well as for the purpose of holding a towel.

Other objects and features of the invention will more fully appear from the following detail description taken in connection with the accompanying drawing which illustrates a single embodiment thereof, and in which:

Figure 1 is a view in elevation of a towel holding device embodying the features of this invention;

Figure 2 is a side view of the device showing the clamping instrumentalities in unclamped relation and a towel having its end threaded into the device;

Figure 3 is a horizontal sectional view showing the manner in which the clamping plate is slidably mounted on the frame, taken substantially on line III—III of Figure 1; and

Figure 4 is a fragmentary sectional view showing the clamping instrumentalities in clamped position on the towel or other article secured therein.

As shown on the drawing:

In the illustrated embodiment of this invention, the device is disclosed as having a frame structure which is preferably formed of a single length of wire. At the mid-point, the single length of wire is bent to define an eyelet 10 by means of which the device may be supported on a wall or other structure. From this eyelet the sides of the frame 80 are formed by extending the wire in diverging relation to form legs 11 and 12 which are deflected as shown at 13 and 14 to form parallel end portions which lie in the same plane. The ends of the portions 13 and 14 are anchored in a transversely extending bar 15 which is preferably of circular cross-section. When using a fixed bar of circular cross-section, the center lines of the portions 13 and 14 should coincide with a diameter of the bar in order that the bar will be symmetrical 85 placed on either side of the frame structure.

Slidably associated with the frame is a substantially semi-circular plate 16 which is provided at each end with an elongated aperture 17, these apertures respectively receiving therethrough the parallel portions 13 and 14 of the frame. It will be observed that the apertures are disposed in alignment between one side of the plate 16 and its longitudinal center line. With 100 this arrangement, as shown in Figure 2, the plate 17 will project a greater amount on one side of the plane of the frame than it does on the other side. Moreover, the inner surface 18 of this plate, the surface 18 cooperating with the outer 105

surface of the bar 15, is of a curvature corresponding to that of the outer surface of the bar 15. This arrangement enables the plate to be moved to clamping position, in which position the 5 plate and bar are in nested relationship with the plate circumferentially engaging substantially 180° of the bar surface.

In using the device of this invention for supporting an article, such as a towel 19, one end of 10 the towel is inserted in the frame between the parallel portions 13 and 14 and overlying the curved plate 16, this inserted end being carried back under the plate 18 and over the bar 15, as shown in Figure 2. In the unclamped position, 15 the lowermost edge of the plate 18 will strike against the bar 15, when the plate is moved towards clamping position. Further movement of the plate 18 will cause the plate to shift sufficiently to enable the lower edge of the plate to pass 20 around the bar 15. This shifting is clearly shown by dotted lines in Figure 2. In Figure 4, the plate 18 is shown in fully clamped position with the bar 15.

With the end of a towel or other article clamped 25 in the device, as shown in Figure 4, the force of the body portion of the article causes the plate 18 to firmly grip the end of the towel or article which is disposed over the bar 15 underneath the plate 18. Moreover, if the body portion of 30 the towel is raised to a position normal to the plane of the frame and a pulling force is exerted during the use thereof, the uppermost edge on the plate will tend to be forced upwardly and the lower edge downwardly, the plate tending to ful- 35 crum at its sliding connection. This action causes the plate to increasingly grip the end of the towel as the pull is increased.

From the foregoing description, it will be apparent that this invention provides a fastening 40 device which is admirably adapted for use as a towel holder, which is devoid of elements which would pierce and have a tendency to tear or otherwise damage the towel or article being supported

in the device; which is so constructed that the 80 towel will be more firmly gripped as the pull thereon is increased; and a supporting device which is so constructed that the clamping instrumentalities may be easily actuated to clamped and unclamped position.

Now, it is, of course, to be understood that although I have described in detail the preferred embodiment of my invention, the invention is not to be thus limited but only insofar as defined by the scope and spirit of the appended claims. 85 I claim as my invention:

1. A device of the character described, comprising a wire frame including spaced parallel side portions, a bar secured at its ends to said portions, and a curved plate having its ends slidably connected to said portions for movement into clamped and unclamped relationship with the bar, one side of said plate projecting past 90 the plane of the frame a greater amount than 95 the other side.

2. A device of the character described comprising a wire frame including spaced parallel side portions, a bar secured at its ends to said portions, and a curved plate having apertures adjacent its 100 ends, for slidably receiving said portions, whereby 105 said plate may be moved into clamped and unclamped relationship with said bar, said apertures being disposed in alignment between one side of the plate and its longitudinal center line, 110 whereby the plate projects past the plane of the frame a greater amount on one side than the other.

3. A device of the character described comprising spaced side members, a bar of circular cross- 110 section interconnecting said side members, a 115 plate slidably supported on said members for movement into and out of surface engagement with said bar, said plate being transversely curved to define a clamping surface for circumferentially engaging substantially 180° of the surface of said bar.

VINCENT PANETTIERE.
